193,752

ASH TRAY

George T. James, San Fernando, Calif., assignor to Glad-ding McBean & Co., Los Angeles, Calif., a corporation of California

Filed Oct. 9, 1961, Ser. No. 67,014

Term of patent 14 years

(Cl. D85—2)

FIG. 1 is a top view of an ash tray showing my new design;

FIG. 2 is a side view thereof;

FIG. 3 is a front view thereof; and

FIG. 4 is a section being taken along plane IV—IV in FIG. 1.

I claim:

The ornamental design for an ash tray, substantially as shown.

References Cited in the file of this patent

UNITED STATES PATENTS

D. 87,522 Jolly ----- Aug. 9, 1932

OTHER REFERENCES

Sports Illustrated, Apr. 11, 1960, page 31, photograph of "Candlestick Park," bottom right.